A. W. OLSON

FASTENING DEVICE FOR CABLES

Filed June 19, 1922

Inventor

Adolph W. Olson

By *Watson S. Coleman*
Attorney

UNITED STATES PATENT OFFICE.

ADOLPH W. OLSON, OF MCINTOSH, MINNESOTA.

FASTENING DEVICE FOR CABLES.

Application filed June 19, 1922. Serial No. 569,222.

To all whom it may concern:

Be it known that I, ADOLPH W. OLSON, a citizen of the United States, residing at McIntosh, in the county of Polk and State 5 of Minnesota, have invented certain new and useful Improvements in Fastening Devices for Cables, of which the following is a specification, reference being had to the accompanying drawings.

10 This invention relates to locking devices and more particularly to locking devices for flexible members, such as cables.

An object of the invention is to provide a device of this character wherein the ends or 15 one end of a rope or cable may be positively locked and firmly held, regardless of the strain applied to the cable or rope.

Another object of the invention is to provide a locking device of this character including a clamp carried by one portion of a cable and stop means carried by another cable or opposite end of the cable to which the clamp is connected, said stop member being adapted to engage the clamp to prevent 25 slipping of the cable within the clamp.

It is a further object of the invention to provide a device of this character including a clamp adapted to be carried by one end of the cable, the clamp having jaws and a clamping lever, said jaws being adapted to receive the opposite end of the cable, the jaws being urged into engagement with said opposite end of the cable by the clamping lever, and means carried by the opposite end of the cable for preventing longitudinal movement of said opposite end of the cable. 30

It is still a further object of the invention to provide a locking device of this character including a clamp, the jaws of which are normally urged toward each other into clamping engagement with an object upon movement of the locking lever of the clamp to its closed position, said lever being provided with means for securing the same to the clamp in its locked position. 40

With these and other objects in view, the invention consists in the improved construction and arrangement of parts to be herein-after more particularly described, fully 50 claimed and illustrated in the accompanying drawings, in which:—

Figure 1 is an enlarged side elevation of a

fastening device constructed in accordance with an embodiment of the invention;

Figure 2 is an end elevation of the clamp 55 partly closed;

Figure 3 is a section taken on the line 3—3 of Figure 1;

Figure 4 is a plan view of the clamp in its open position. 60

Referring to the drawings, 5 designates a flexible member or cable which may be constructed of any material. It is of course obvious that portions of this device may be used on a single cable or separate cables, according to the work. For the purpose of illustration, however, the device is shown on a single cable. In connection with the cable, a clamping device is used, said clamping device comprising a body member consisting of a sheet of resilient metal stamped to provide a body member 6, having an extension 7 projecting from one side thereof. The side portions 8 and 9 of the body member serve as jaws, the jaw 8 having spaced extensions 10 projecting therefrom, said extensions being coiled to provide hinge knuckles, the knuckles projecting beyond the edge of the jaw 9. In the formation of the clamp of the lock, the body member is bent at its central portion to provide a socket member 11 substantially corresponding in diameter to the diameter of the cable or flexible member to be clamped and adapted to receive one end of the cable. The 70 extension 7 has its marginal edges separated from the jaws 8 and 9 so that said extension may be formed into a ferrule or sleeve adapted to receive the extremity of the cable. The 75

It is a further object of the invention to provide a device of this character including a clamp adapted to be carried by one end of the cable, the clamp having jaws and a clamping lever, said jaws being adapted to receive the opposite end of the cable, the jaws being urged into engagement with said opposite end of the cable by the clamping lever, and means carried by the opposite end of the cable for preventing longitudinal movement of said opposite end of the cable. 80

It is still a further object of the invention to provide a locking device of this character including a clamp, the jaws of which are normally urged toward each other into clamping engagement with an object upon movement of the locking lever of the clamp to its closed position, said lever being provided with means for securing the same to the clamp in its locked position. 85

With these and other objects in view, the invention consists in the improved construction and arrangement of parts to be herein-after more particularly described, fully 90 claimed and illustrated in the accompanying drawings, in which:—

Figure 1 is an enlarged side elevation of a

fastening device constructed in accordance with an embodiment of the invention;

Figure 2 is an end elevation of the clamp 55 partly closed;

Figure 3 is a section taken on the line 3—3 of Figure 1;

Figure 4 is a plan view of the clamp in its open position. 60

Referring to the drawings, 5 designates a flexible member or cable which may be constructed of any material. It is of course obvious that portions of this device may be used on a single cable or separate cables, according to the work. For the purpose of illustration, however, the device is shown on a single cable. In connection with the cable, a clamping device is used, said clamping device comprising a body member consisting of a sheet of resilient metal stamped to provide a body member 6, having an extension 7 projecting from one side thereof. The side portions 8 and 9 of the body member serve as jaws, the jaw 8 having spaced extensions 10 projecting therefrom, said extensions being coiled to provide hinge knuckles, the knuckles projecting beyond the edge of the jaw 9. In the formation of the clamp of the lock, the body member is bent at its central portion to provide a socket member 11 substantially corresponding in diameter to the diameter of the cable or flexible member to be clamped and adapted to receive one end of the cable. The 70 extension 7 has its marginal edges separated from the jaws 8 and 9 so that said extension may be formed into a ferrule or sleeve adapted to receive the extremity of the cable. The 75

It is a further object of the invention to provide a device of this character including a clamp adapted to be carried by one end of the cable, the clamp having jaws and a clamping lever, said jaws being adapted to receive the opposite end of the cable, the jaws being urged into engagement with said opposite end of the cable by the clamping lever, and means carried by the opposite end of the cable for preventing longitudinal movement of said opposite end of the cable. 80

It is still a further object of the invention to provide a locking device of this character including a clamp, the jaws of which are normally urged toward each other into clamping engagement with an object upon movement of the locking lever of the clamp to its closed position, said lever being provided with means for securing the same to the clamp in its locked position. 85

With these and other objects in view, the invention consists in the improved construction and arrangement of parts to be herein-after more particularly described, fully 90 claimed and illustrated in the accompanying drawings, in which:—

provide an extension. The extension is coiled to form a hinge knuckle 14 adapted to be disposed between and register with the openings of the hinge knuckles formed by the extensions 10. The lever is then bent adjacent its end portion 13 substantially at right angles to said end portion, while the opposite end portion 15 is likewise bent in angular relation to the central portion of the lever, the last bent portion being curved according to the diameter of the socket 11. The extremity of the end portion 15^a is provided with a bead 16 which not only forms the finger piece, but assists in locking the lever in a manner to be hereinafter described. The knuckle 14 is pivoted by means of a pintle 16 passing through the hinge knuckles of the jaw 8. The end portion 13, that is, that portion of the lever from the hinge knuckle 14 to the junction of the central portion with the end portion 13, is considerably less in length than the distance between the upper edges of the jaws 8 and 9 so that when the lever 12 is swung over the jaw 9, said jaw will be urged toward the jaw 8, because of the shortness of the end portion 13 as above described.

In view of the fact that the jaws are normally swung outwardly, when the end portion 15 of the locking member is engaged with the bottom of the socket member 11, the jaw 8 likewise will be urged toward the jaw 9 as the end portion 15 is inclined inwardly toward the central portion of the lever. This naturally causes both jaws to bind on the cable by urging both jaws simultaneously toward each other. This locking action is assisted by the bead 16 as it reinforces the end 15^a and prevents the same from springing outwardly. Furthermore, when the lever is swung to its closed position, the end portions 15 will urge the end portions 13 into engagement with the upper edge of the jaw and through the cooperation of the contact of the end portion 13 with said jaw and the frictional engagement of the end portion 15 with the body member 6, accidental movement of the lever is prevented. To permit all possible strain to be applied to the cable clamped by the jaws 8 and 9, the opposite end of the cable 6 is provided with stop members 17, said stop members being constructed in the form of rings which are clinched or otherwise secured to the cable in spaced relation to each other, the space between the stop members corresponding to the width of the jaws 8 and 9. Any number of these stops may be used, according to the variety of adjustment desired.

In operation of the device the end of the cable provided with the stops 17 is placed between the jaws 8 and 9 so that one stop is disposed at each end of the jaw and adapted to engage said jaws. The lever 12 is then swung over the end of the cable to be secured

and locked as above described. This firmly holds the end of the cable within the clamp. However, should abnormal strain be applied to the cable, the stop members will come in contact with the ends of the jaws and thereby limit or prevent longitudinal movement of the cable and prevent breaking of the grip of the jaws on the opposite end of the cable.

From the foregoing it will be readily seen that this invention provides a novel form of fastener capable of being used any place desired to connect two ends of a cable to each other, or wherein it is desired to connect two cables. It is especially recommended for use in connection with the side connecting members of automobile anti-skid devices, as it provides a lock which is compact and which can be readily operated and adjusted to suit the size of the wheel. All of these features are possessed by a device that is exceedingly simple in construction and positive in its locking action.

What is claimed is:—

1. In combination with a flexible member, a clamp carried by one end of said member, stop members carried by the opposite end of the flexible member in spaced relation to each other, said clamp being arranged to receive and clamp the second mentioned end portion of the cable, said stop members preventing movement of the second mentioned end portion of the cable from its clamped position within the jaws.

2. A fastening device comprising a clamp including a pair of resilient jaws, a lever carried by the end of one of said jaws and adapted to extend over the end of the opposite jaw for urging said jaws toward each other, a flexible member having stop rings, carried by its end portion in spaced relation to each other, one of the portions of said end portion between said rings being adapted to engage the jaws of the clamp, the lever of said clamp being adapted to urge the jaws into binding engagement with said portion of the cable, the stop rings of said portion of the cable being arranged to engage the end portions of the clamp to prevent longitudinal movement of said cable in either direction.

3. In combination with a cable, stop rings carried by one end portion of said cable, said rings being spaced from each other longitudinally of said end portion, a clamping device consisting of a resilient sheet of material bent to provide a pair of jaws, said sheet having an extension, the extension being formed into a ferrule adapted to receive the opposite end of the cable, means for permanently screwing said opposite end of the cable within the ferrule, a substantially U-shaped clamping lever pivoted to one of said jaws and adapted to extend over the opposite jaw, said jaws being adapted to receive the portion of the first

mentioned end of the cable disposed between said rings to prevent disengagement of the stop rings from the jaws and to clamp said jaws in engagement with the first mentioned end of the cable.

4. In combination with a flexible member, a clamp carried by one end of said member, stop members carried by the opposite end of the flexible member in spaced relation to

each other, said clamp being arranged to receive and clamp the second mentioned end portion of the cable, said stop members preventing movement of the second mentioned end portion of the cable in either direction from its clamped position between the jaws. 15

In testimony whereof I hereunto affix my signature.

ADOLPH W. OLSON.
